UNITED STATES PATENT OFFICE.

KARL WINKLER, OF NEWARK, NEW JERSEY, ASSIGNOR TO MOHAWK BRUSH COMPANY,
A CORPORATION OF NEW YORK.

CAM MECHANISM.

1,228,730.

Specification of Letters Patent. Patented June 5, 1917.

Application filed June 28, 1915. Serial No. 36,781.

To all whom it may concern:

Be it known that I, KARL WINKLER, a citizen of the German Empire, and a resident of Newark, in the county of Essex and State 5 of New Jersey, have invented certain new and useful Improvements in Cam Mechanisms, of which the following is a specification.

This invention relates to improvements in 10 a cam mechanism which will find useful application in brush-making machines, such an embodiment being an improvement over the invention disclosed in my United States Patent No. 1,081,709, dated December 16th, 15 1913. The present invention has for an object to provide means for longitudinally and laterally moving the brush-carrying table either in a reciprocating or an oscillating manner, according to the type of machine, for the purpose of drilling and filling 20 the brush blocks, which means will be adjustable, so that new designs of brushes may be produced without requiring the supplying of any new parts, thereby increasing the 25 producing possibilities of the machine without materially increasing the cost, and which will impart a more accurate movement to the table than has heretofore been possible with the known types of machines, thereby 30 enabling the machine to produce better brushes. Another object is to produce a machine of this character which will be simple in construction and manufacture, and which improvements may be readily applied 35 to the old types of machines at present in use.

With these and other objects in view, my invention is shown in the accompanying drawings, and will be hereinafter more fully 40 described with reference thereto, and finally pointed out in the claims.

In the accompanying drawings,

Figure 1 is a side elevation of a brush-making machine with my improvements incorporated therein;

Fig. 2 is a side elevation of my invention with parts broken away;

Fig. 3 is a sectional view on the line 3—3 of Fig. 2, showing one side only, the other 50 side being identical;

Fig. 4 is a side elevation of a modified form of construction;

Fig. 5 is an enlarged detail view with parts broken away;

Fig. 6 is an enlarged sectional view taken 55 on the line 6—6 of Fig. 4; and

Fig. 7 is a sectional view showing the application of the opening and closing means shown in Figs. 1, 2 and 3 to the form shown in Figs. 4 to 6.

Similar reference characters indicate corresponding parts throughout the several figures of the drawings.

Referring to the drawings, and more particularly to Fig. 1 thereof, the brush machine, which is shown by way of illustration and is of the well known type, comprises a table 10 and a drilling tool 11, a tuft-filling mechanism 12 for filling the socket-holes with tufts of bristles, all mounted above a support 13. A single table 10 is shown, which is provided with the necessary clamping devices 14 for securing the brush backs in position for the drilling and filling operations.

The drilling mechanism 11 and the tuft-filling mechanism 12 are both driven by a shaft 15 that receives rotary motion from a belt and pulley transmission 16, 17, from an overhead power shaft (not shown). The 80 driving pulley 17 transmits by a connecting rod 18 reciprocating motion to a vertically guided slide-piece 19, which engages by means of a pair of teeth 20 at its lower end the toothed circumference of a pattern wheel 21, the shaft 22 of which is supported in bearings 23 at the rear part of the supporting frame 13, so as to impart a step-by-step rotary motion to the said pattern wheel.

On each of the side surfaces of the said 90 pattern wheel there are provided the cam tracks 24 and 25 respectively. These cam tracks comprise a series of closely arranged pins or projections 26, which are secured into holes 27 provided in the wheel. The 95 particular course taken by these projections or pins serve with the coöperation of lever mechanisms hereinafter described to impart to the brush-supporting table 10 the desired longitudinal and lateral motion above referred to, so that it will be seen that by changing the design of the cam tracks, the manner in which the holes are drilled and the tufts filled into the same may also be changed, such a change being required for 100 instance in the manufacture of an oval brush, as distinguished from a rectangular one. For accomplishing this change, it is 105

only necessary that a new series of holes be drilled in the sides of the pattern wheel and the pins placed into these new holes, or a pattern wheel may be supplied, in the first instance, with several series of holes into which the pins may be interchangeably placed. The wheel may also be provided with a plurality of closely arranged holes, not following any particular design, in 10 which case the pins could be universally moved about to represent any design that may be required.

Each of the said pins 26 is in radial alignment with the straight surface of one of the 15 toothed projections forming the circumference of the wheel, so that with each step-by-step rotary motion of the wheel one of the pins coincides with a fixed point on the machine. The pattern wheel 21 may be turned 20 independently of the driving shaft, if desired, by a gear-wheel 93, pinion 94 and crank-handle 95, for the preliminary adjusting of the machine preparatory to starting it for work.

25 Slidably mounted on rollers 28 mounted in bearings 29 on the frame of the machine are the reciprocating members 30 and 31. Rollers 28^a and 28^b mounted above the said members serve to prevent upward movement of the same. The member 30 is connected by means of the levers 32 with the brush table 10, and by its movement to-and-fro imparts longitudinal motion to the 30 table, and the member 31 is connected to the same by the levers 33, and imparts to the same a lateral movement, as is well known. Mounted on each of the said reciprocating members are provided equalizing devices 34 and 35 secured to the same by means of 35 screws 36. The said equalizing devices comprise opening and closing members 37 and 38 mounted between the guide-pieces 39 on the members 30 and 31. For holding the said members in closed position, there are 40 mounted between the outer ends of the same and the upstanding ends 40 and 41 of the members 30 and 31 helical springs 42 and 43.

Mounted on the underside of the members 30 and 31 are provided stub shafts 44, which 50 are engaged by a bore 45 provided in the upper end of shafts 46. Ears or lugs 47 and 48 are provided at each side of the said shaft, which are connected by means of links 49 and 50 to bell-crank levers 51 and 52 55 provided within the members 30 and 31. The bell-crank levers are in turn connected to the members 37 and 38 by links 53 and 54 provided within suitable recesses within the said members, so that by rectilinear reciprocating motion of the shaft 46 with respect to the stub shaft 44, the said members are intermittently forced away from each other against the force of the springs 42 and 43.

In the upper surface of the members 37 60 and 38, at the adjacent ends thereof, there

are provided recesses 55 and 56, within which are provided the contact members or feelers 57 and 58. These contact members 57 and 58 are pivotally secured within the said recesses at 59 and 60, and in operative 70 position project outwardly therefrom, being held in position by the screws 61 and 62, but when it is desired for any reason to make the same inoperative, they may be moved entirely within the recesses by loosening of 75 the said screws 61 and 62. The ends of the said contact members, in operative position, are spaced apart a distance equal to the thickness of the pins, so that during the rotation of the pattern wheel the said pins 80 pass between the said contact members. The projecting portions of the said members are provided with upstanding guiding means 63 and 64, having inner inclined surfaces, which 85 serve to guide the pins between the contact members.

For reciprocating the shaft 46, I have provided connected to the slide-piece 19 a rod 65, which engages a trip-lever 66 pivoted to a bracket 67 of the frame 13. The outer end of the trip-lever engages beneath a platform 68, upon which rests a roller 69 at the lower end of the said shaft 46, so that each time the slide-piece operates, the platform 68 is lifted by the trip-lever, and in turn 95 the shaft 46 is lifted, opening the members 37 and 38. Simultaneously the pattern wheel is rotated one space by the teeth 20.

It will be seen, therefore, that upon each opening movement of the members 37 and 38 a new pin comes between the contact members or feelers 57 and 58, which pin may be either to one side or the other or in the same place with respect to the previous pins, depending, of course, on the particular 105 curve of the cam-track at that point. Assuming for instance, that the next pin is to the left of the previous pin, the contact member on the left will hit the same before the one on the right, and as the left member is 110 prevented from further movement by the pin, the right member by force of the springs is drawn to the pin, carrying with it the member 34 on one side, or 35 on the other, upon which the same is mounted, and 115 the reciprocating member 30, or 31, as the case may be, which in turn moves the brush table 10 either longitudinally or laterally. Should the pin be to the right of the previous pin, the action will be reversed, while 120 should the same be in the same relative position there will be no movement of the said members. A pair of tables, upon which are provided two sets of brush blocks, are moved simultaneously, one being beneath 125 the boring mechanism, and the other beneath the bristle-filling mechanism, so that while holes are being bored in one set of brushes, bristles are being placed in the holes of the second set.

In Figs. 4, 5 and 6, I have shown a slightly modified form of my invention, in which I have provided two pattern wheels 70 and 71, one for imparting to the brush table the longitudinal movement, and the other for the lateral movement, and between the same is arranged a toothed wheel 70^a, which is intermittently engaged by suitable mechanism for rotating the said wheels step by step. In the peripheries of the said wheels are provided transverse grooves 72, in each of which are secured dove-tailed blocks 73 by means of tightening screws 74. The said blocks are provided with rectangular projections 75 having rounded lower corners 91, the said projections corresponding to the pins 26 of the first-described form of construction. The said blocks 73 are so arranged within the said grooves with respect to each other, as to form a cam track, the direction of which determines the movement of the brush table.

When it is desired to make a new pattern, a design of the brush is placed on the table and the table is manually moved, so that the boring device engages each hole, and at the same time the pins are placed on the pattern wheel in the positions indicated by the movement of the levers. Each pin, as will be understood, corresponds to a hole to be bored in the brush block, so that if for any reason it is desired to make the same design of brush with less bristles, it is only necessary to further space the pins from the periphery of the wheel, so that the desired number of pins may be removed, or a section of the pins may be removed and the machine operated by hand across this section.

Coöperating with the said cam tracks are the reciprocating members 76 and 77 mounted in the bearings 78 and 79 of the frame, and connected to the brush tables by a system of levers 80, 81, 82, and 83, 84 and 85. Grooves 86 are provided in the said reciprocating members, in which are disposed the dove-tailed blocks 87 secured therein by screws 88. Projections or feelers 89, 90 are provided on the said block, between which pass the projections 75 of the cam track, the space between the two projections 89 and 90 being approximately equal to the thickness of the projections 75. The lower corners of the said projections 75 are rounded, as at 91, or, if desired, may be provided with small rollers, and the inner surfaces of the projections 89 and 90 are inclined, as at 92, to enable the said projections 75 to be guided between the said members 89 and 90. The projections may, if desired, be round, as in the first described form of construction, and may also be rotatable. The distance between the projections 75 is such that one of the said projections will be entirely disengaged from the

projections 89 and 90, before the next succeeding projection engages the inclined surfaces 92.

The operation of this embodiment is the same as that described with reference to the first embodiment, with the exception that there is no opening and closing action, the reciprocation of the members 76 and 77 being brought about by frictional contact of the cam track with the reciprocating members. It will be understood, however, that either of the forms of pattern wheels may be used equally well with either of the forms of reciprocating members. Fig. 7 illustrates the application of the opening and closing reciprocating members in the form shown in Figs. 4 to 6.

It will be seen that with the use of my improvements, the operation of the brush table is brought about in a more accurate and expeditious manner, and any number of designs of brushes may be manufactured with the same pattern wheel by simply changing the direction of the cam track. With the machines heretofore in use, it was necessary to employ separate pattern wheels for each form of brush manufactured, and these pattern wheels were produced at great expense and waste of time in the making, whereas with my invention the expense is entirely obviated and several hours only in time are required to change the design.

I have illustrated preferred and satisfactory forms of my invention, but it will be understood that changes may be made therein, other methods bringing about the operation of the opening and closing members, and of the rectilinear reciprocating shaft 46 resorted to, all within the spirit and scope of my invention, so that I do not wish to be limited to the particular construction shown, except as may be required by the claims.

Having thus described my invention, I claim as new and desire to secure by Letters Patent:—

1. In a cam mechanism, the combination with mechanism to be operated, of intermittently rotatable means provided with a plurality of spaced retaining tracks, relatively near each other, individual means slidably engaged with each of said tracks, and adjustable with relation to each other within the extremities of said tracks, and projecting outwardly from the surface of said rotatable means, means for securing the position of said individual means to form a cam track, and means coöperating with said track adapted to be reciprocated thereby to transmit movement to said mechanism.

2. In a cam mechanism, the combination with mechanism to be operated, of intermittently rotatable means provided with an annular cam surface, a plurality of spaced grooves therein, relatively near each other,

and extending transversely of said cam surface, individual slide blocks mounted within said grooves, adjustable within the extremities of said grooves, and provided with 5 projecting lugs, said lugs forming a cam track about said cam surface adapted to be changed by movement of said slide blocks, means for securing the position of said slide blocks, and means coöperating with said 10 track adapted to be reciprocated thereby to transmit movement to said mechanism.

3. In a cam mechanism, the combination with mechanism to be operated, of intermittently rotatable means having a relatively 15 wide peripheral surface, and provided on said peripheral surface with a plurality of spaced and transverse grooves therein, relatively near each other, individual slide means removably secured within each of 20 said grooves, adapted to project outwardly from the periphery of said rotatable means, and adapted to be individually adjusted with relation to each other; within the extremities of said grooves to form a cam 25 track, means coöperating with said track adapted to be reciprocated thereby, and to transmit movement to said mechanism.

4. In a cam mechanism, the combination with mechanism to be operated, of intermittently rotatable means provided with a plurality of spaced retaining tracks, relatively 30 near each other, individual means slidably engaged with each of said tracks, and adjustable with relation to each other within 35 the extremities of said tracks, and projecting outwardly from the surface of said rotatable means, means for securing the position of said individual means to form a cam track, and means coöperating with said 40 track adapted to be reciprocated thereby,

and comprising a slideable member, opening and closing members carried thereby, means for opening the said members simultaneously with the intermittent movement of said rotatable means, means for closing the 45 members between the movements of the said rotating wheel, spaced guiding means carried by the said opening and closing members, the spaced projecting means of the cam track adapted to intermittently engage 50 between the said guiding means upon opening of said members, the said guiding means adapted to engage said projecting means upon closing of said members, the relative positions of the said projecting means causing 55 corresponding reciprocatory motion of said slideable member, the movement of said slideable member adapted to transmit movement to said mechanism.

5. In a cam mechanism, the combination with mechanism to be operated, of movable means provided with a plurality of spaced retaining tracks, relatively near each other, individual means slidably engaged with each of said tracks, and adjustable with relation to each other within the extremities of said tracks, and projecting outwardly from the surface of said rotatable means, means for securing the position of said individual means to form a cam track, and 70 means coöperating with said cam track adapted to be moved thereby to transmit movement to said mechanism.

In testimony that I claim the foregoing as my invention, I have signed my name in 75 presence of two subscribing witnesses.

KARL WINKLER.
